UNITED STATES PATENT OFFICE.

CALVIN H. LUCY, OF BALTIMORE, MARYLAND, ASSIGNOR TO THE SINGER MANUFACTURING COMPANY, A CORPORATION OF NEW JERSEY.

FEEDING MECHANISM FOR SEWING MACHINES.

Application filed March 11, 1919. Serial No. 281,951.

To all whom it may concern:

Be it known that I, CALVIN H. LUCY, a citizen of the United States, residing at Baltimore, State of Maryland, have invented 5 certain new and useful Improvements in Feeding Mechanism for Sewing Machines, of which the following is a specification, reference being had therein to the accompanying drawings.

10 This invention relates to sewing machines and especially to the work-advancing mechanism thereof commonly known as the "feed."

15 In the application of facings to the neck portions of shirts and in other similar operations connected with the manufacture of wearing apparel, it is frequently desirable to make two or more rows of stitches along curved lines any two of which are spaced 20 a uniform distance apart, or concentrically in the special case of circular seaming. This has heretofore been done in separate operations first one row of stitches being completed and then another. So far as is 25 known it has never been accomplished satisfactorily in a single operation on either wide or narrow gauge multiple needle machines.

30 The present invention aims to provide a new form of feeding mechanism for sewing machines employing a plurality of needles which will enable the operator to stitch on a curve in separate rows, each spaced a uniform distance from the adjacent row and 35 the stitches on the outside being longer than those on the inside, in order to reduce the number of operations required to finish a garment.

40 It aims further to provide a new combination of multiple needle stitch-forming mechanism and feeding mechanism which is simple but efficient in operation and of such a construction that the established organization of the component instrumentalities in a 45 sewing machine may be used in their entirety, thus attaining the new and useful results sought without sacrifice of any of the advantages in efficiency realized by the development of the art up to the present time.

50 The invention further aims to provide a construction and arrangement of the component parts of the feeding mechanism in which adjustment for a wide range of curvatures of seaming may be made with facility.

55 The construction comprises, broadly

stated, work-engaging elements arranged and actuated to advance the work different distances under each of a plurality of needles. The specific construction comprises a four-motion feeding mechanism including 60 a feed-dog carrying bar upon which is fulcrumed flatwise a member carrying a number of serrated feed-dog sections which are swung in unison in concentric curves through a link operatively connected to a 65 rocking lever whose throw may be varied as desired.

The invention is illustrated in the accompanying drawings in which Fig. 1 is a plan view of a machine showing as much of the 70 mechanism as is necessary to illustrate the application of the invention thereto. Fig. 2 is an end elevation thereof. Fig. 3 is a front elevation of the same. Fig. 4 is a detail of the adjustment mechanism for varying the curvilinear movement of the feed-dog and Fig. 5 is a plan view of the throat-plate and feed-dog sections with the latter shown in solid and dotted lines respectively 75 at the opposite extremes of its work-advancing stroke.

The principle of the invention is present in the form of the invention shown in the accompanying drawings to illustrate one 80 concrete application of the invention but the specific embodiment shown is not to be taken as limiting or constricting the scope of the invention.

The invention is illustrated applied to a two-needle two-looper machine of the chain-stitch type making two independent seams, the needles, indicated at 1, being secured in laterally spaced relationship abreast of one another in a clamp 2 on a needle-bar 3 actuated in any well known manner, and the loopers, indicated at 4, being secured to looper-carriers 5 which may also be actuated in any suitable manner. A presser-foot 6 with a flat sole portion is provided and it is suitably apertured in register with needle-holes 8 in a throat-plate 9 which is secured to a cross-bar 10 sustained by fixed standards 11 rising from the bed-plate 12 of the machine frame.

The feeding mechanism includes a rocking 105 frame 15 fulcrumed on a fixed pin 16 and actuated through a pin and socket connection 17 from an eccentric 18 on the main-shaft 19. The eccentric 18 may be of any conveniently adjustable type so as to vary 110

the throw of the pin 20 in the upper free end of the rocking frame and thereby also to vary the throw or feeding movement of a feed-dog carrying bar 21 fulcrumed on said pin 20. Vertical components of motion are imparted to the feed-dog carrying bar 21 by an eccentric 22 on the main-shaft through the agency of a pin and socket connection 23 of a form old in the prior art.

10 The above described construction is all old and well known and for further information concerning the same reference is hereby made to patent to DeVoe No. 1,085,801, granted Feb. 3, 1914, on the looper 15 operating mechanism and reissue patent to DeVoe, No. 14,218, granted Nov. 28, 1916, on the four-motion feeding mechanism.

By a shouldered stud-screw 24 a feed-dog plate 25 at one side is fulcrumed on the U-shaped free end 26 of a plate 26' screwed at 26" to the feed-dog carrying bar 21 and at its other side this feed-dog plate 25 carries a ball-ended stud 27 which is connected by the link 28 to a shouldered stud-screw 29 threaded into the upper end of a rock-lever 30 in whose lower end is threaded a shouldered stud screw 31 which is fulcrumed in a fixed part of the frame of the machine. The rock-lever 30 has a channel 32, see Figs. 30 1 and 4, which receives an actuating slide-block 33 swiveled or pivoted on a pin 34 extending laterally from a block 35 which is adjustable in a vertically disposed channel 36 provided in a guide-post 37 screwed fast to and depending from the plate 26' fixed to the feed-dog carrying bar 21. Adjustment of the block 35 in the channel is effected by turning the screw 38 threaded into the block and suitably held from axial displacement relative to the feed-dog carrying bar in which it is mounted.

35 The feed-dog plate 25 carries a plurality of serrated sections or work-engaging members 39 which pass through slots 40 in the throat-plate. The relation between the paths in which the individual sections of the feed-dog move to the paths of the needles is clearly portrayed in Figs. 1 and 5 of the drawings.

40 In the operation of the machine the fulcrum 24 of the feed-dog plate 25 receives four motions in a manner that will be well understood since the stud-screw 24 is threaded into the feed-dog carrying bar 21. 45 The horizontal components of the four-motion feed are compounded with the curvilinear motion imparted to the feed-dog plate by the link 28 which turns the plate on its fulcrum during the feed movement of the four-motion mechanism. The extent of curvilinear movement as well as the rate or velocity thereof imparted to the feed-dog plate 25 varies with the position of the actuating slide-block in the rocker 30, the farther 60 the block 33 is away from the fulcrum 31

of the rock-lever the less the curvilinear movement and vice versa. This curvilinear movement may be made practically negligible, if desired, thus permitting straight away stitching on the machine. Obviously by 70 suitably proportioning the parts different curvilinear movements may be made as great as commercial demands require. The depending guide-post 37 being arranged at substantially right angles to the feed-dog 75 carrying bar 21, the swivel pin 34 and block 35 will have substantially the same throw in a horizontal direction (parallel to the plane in which the work is moved) in any position to which the parts may have been adjusted through the screw 38. While the lift of the feed-dog carrying bar acts intermittently to shift the actuating slide-block 33 in the rocker 30 the shifting movement is negligible in amount owing to the proximity of 80 the bar 37 to the hinge pin 20 about which the feed-dog carrying bar 21 swings during its vertical movement.

By compounding with the horizontal components of motion of a four-motion type of feeding mechanism a curvilinear motion in a plane parallel with the plane in which the work is advanced step-by-step, or in other words, by swinging the feed-dog sections about a fulcrum which is itself moved back and forth, the feed-dog sections have a resulting movement in a circle, or approximately in a circle, of a much greater radius than if the fulcrum-screw 24 was fixed 95 against horizontal movement.

100 Obviously the feed-dog sections may be made to move in curved paths opposite to those illustrated in the drawings by reversing the relative location of the fulcrum 24 and actuating link 28.

It will also be noted that the curvilinear movement of the feed-dog sections may be varied in two ways, through the feed eccentric 18 in the main-shaft and through the shiftable actuating slide block 33. Change 110 in the curvilinear movement of the feed-dog may thus be effected whether the stitch be long or short.

While the invention is disclosed in its preferred form it will be distinctly understood 115 that the principle thereof may be incorporated in metal in a great many ways. As far as the invention is understood at present it contemplates broadly speaking the idea of simultaneously moving a plurality of work-engaging members, no matter where located or how actuated, different effective feeding distances past spaced needles in order to seam on a curve. And the kind of stitch-forming mechanism employed is immaterial 120 as long as there are two or more needles arranged out of alignment in the direction of feed i. e., in the direction of advance of the work. For example it contemplates the use of a plurality of needles with one or 125

more loop-takers for making a series of separate seams or a single compound covering seam.

Having thus set forth the nature of the invention what I claim herein is:—

- 5 1. In a sewing machine, in combination, stitch-forming mechanism including a plurality of spaced needles, and work advancing mechanism including a presser member and cooperating four-motion feed-dog sections adjacent the respective needles and movable at the same angular velocity in concentric horizontal paths to feed the work in a curved path without distortion. 10
- 15 2. In a sewing machine, in combination, stitch-forming mechanism including a plurality of spaced needles for making separate rows of stitches, and work-feeding mechanism including a presser member, and work engaging portions with means for moving the latter up and down into and out of engagement with the material and in separate horizontally curved paths while in engagement with the material, whereby a plurality 20 of curved rows of stitching may be made on the machine at the same time. 25
3. In a sewing machine having stitch-forming mechanism including spaced needles, work feeding mechanism including a feed-dog carrying bar, a feed-dog on said bar and having a plurality of spaced serrated sections adapted to engage the work adjacent the respective needles, means for imparting feeding and lifting movements to the bar and the dog thereon, and means for moving said dog in a curved path in parallelism with the plane in which the work is advanced. 30
4. In a sewing machine, in combination, stitch-forming mechanism, a presser-foot, and work advancing mechanism including feed-dog sections, a common carrier for said feed-dog sections, means for imparting lifting and feeding movements to said sections, and means for compounding with the feeding movement of said sections, a curvilinear movement in the plane of movement of the work including a fulcrum and an actuating member for said carrier respectively 45 on opposite sides of the feed-dog sections, and means for operating the actuating member. 50
5. In a sewing machine, in combination, stitch-forming mechanism including a plurality of spaced needles out of alinement in the direction the work is advanced, and means for advancing the work different distances under each needle including a feed-dog carrying bar, means for imparting four-motion to said feed-dog carrying bar, serrated work advancing sections, a common support for said serrated sections, a fulcrum for said common support located at one side of the needle path, and means for oscillating 60 said common support in sequence with the
- four-motion feeding mechanism whereby stitches of unequal length may be made simultaneously. 6. In a sewing machine, in combination, stitch-forming mechanism including a plurality of spaced needles out of alinement in the direction the work is advanced, and feeding mechanism including a plurality of spaced work engaging members adapted to engage the work adjacent the respective needles and means for actuating the same including a four motion mechanism to which the work engaging members are fulcrumed at one side of the needles, and means for actuating said work engaging members about the fulcrum. 70
7. The combination with stitch-forming mechanism including a plurality of needles spaced apart transversely of the direction of seam-formation, of feeding mechanism including a feed-dog arranged to engage the sewed work mainly in rear of the needles, means for imparting feeding and lifting movements to said feed-dog, and means for turning the feed-dog in a plane 80 parallel to the plane of the work during its feeding movement. 85
8. The combination with stitch-forming mechanism including a plurality of needles spaced apart transversely of the direction of seam-formation, of feeding mechanism including feed-dog sections disposed adjacent the respective needles, means for imparting lifting movements to said sections, and means for imparting horizontally curved concentric feeding movements to said sections, whereby the work will be fed in a curved path without distortion. 90 100
9. The combination with stitch-forming mechanism including a plurality of needles spaced transversely of the direction of seam-formation, of feeding mechanism including a feed-dog having relatively fixed portions for engaging the work adjacent the respective needles, means for imparting lifting movements to said feed-dog, and means for moving said feed-dog in the direction of feed and for turning the feed-dog in a plane parallel to the plane of the work during its feeding stroke, thereby feeding the work in a curved path. 105 110
10. Feeding mechanism for sewing machines comprising a feed-bar, lifting means for imparting rising-and-falling movements to the feed-bar, feeding means for imparting feed-and-return movements to the feed-bar, a feed-dog pivoted at one point on said feed-bar to turn in a plane parallel to the plane of the work, and a feed-motion multiplying connection between the feed-bar and another point on said feed-dog. 120 125
11. Feeding mechanism for sewing machines comprising, a feed-dog, means for imparting lifting movements to said feed-dog, and adjustable means for imparting feeding 130

movements to said feed-dog in both a straight and a horizontally curved path, whereby straight-line or curved-line stitching may be accomplished, at the will of the operator.

12. Feeding mechanism for sewing machines comprising a four-motion feed-bar, actuating means therefor, a feed-dog pivoted on said feed-bar to swing in a plane parallel to the plane of the work, and adjustable means driven by said feed-actuating means for swinging said feed-dog relative to the feed-bar during the feeding stroke for curved-line stitching, said means having a range of adjustment permitting a zero swing to be secured for straight-line stitching.

13. The combination with stitch-forming mechanism including a pair of needles spaced transversely of the direction of seam-formation, of feeding mechanism including a plural-section four-motion feed-dog operating on the work adjacent said needles, and means for turning the feed-dog in a plane parallel with the plane of the work and

about a center at one side of the line of seam-formation during the feeding stroke.

14. The combination with a plurality of needles spaced apart transversely of the direction of seam-formation, of a four-motion feed-dog with means for moving it in a path curved in the plane of the work during its feeding stroke, at least a portion of said feed-dog being positioned in rear of the needles to engage the work after it is stitched.

15. The combination with stitch-forming mechanism including a plurality of needles spaced apart transversely of the direction of seam-formation, of feeding mechanism comprising a four-motion feed-dog having spaced work-engaging portions fixed relatively to one another with means for imparting feeding movements to said feed-dog in a path curved in the plane of the work during its feeding stroke.

In testimony whereof, I have signed my name to this specification.

CALVIN H. LUCY.
